AIRTIGHT COVER FOR CONTAINERS

Souren Kazanjian, Woodside, Long Island, N. Y.

Application September 1, 1938, Serial No. 227,879

5 Claims. (Cl. 215—96)

This invention relates to new and useful improvements in an air tight cover for containers.

The invention has for an object the construction of an air tight cover which is characterized by an outer cap for engaging over the neck of a container and associated in a particular manner with an inner cap, an arrangement being provided for tightly clamping the inner cap upon the neck of the bottle.

10 More specifically, the invention contemplates the use of a band of flexible metal disposed between the outer and inner caps and encircling the inner cap and adapted to comprise the means for tightly clamping the inner cap on the neck of the bottle.

A further object of this invention resides in the provision of certain cooperative means between the ends of the band for holding the band in a taut condition.

20 For further comprehension of the invention, and of the objects and advantages thereof, reference will be had to the following description and accompanying drawing, and to the appended claims in which the various novel features of the invention are more particularly set forth.

25 In the accompanying drawing forming a material part of this disclosure:—

Fig. 1 is a side elevational view of an air tight cover constructed according to this invention and shown mounted on the neck of a container.

30 Fig. 2 is a horizontal sectional view taken on the line 2—2 of Fig. 1.

Fig. 3 is a fragmentary vertical sectional view taken on the line 3—3 of Fig. 2.

35 Fig. 4 is a fragmentary vertical sectional view on the line 4—4 of Fig. 1.

Fig. 5 is a fragmentary vertical sectional view on the line 5—5 of Fig. 2.

The air tight cover for containers, according to this invention, includes an outer cap 10 for engaging the neck 11 of a container. An inner cap 12 of relatively flexible material is disposed within the outer cap and is adapted to engage over the neck 11. A band of flexible material 13 is disposed between said caps 10 and 12 and is adapted to clamp the inner cap 12 tightly against the neck 11. Cooperative means are arranged between the ends of the band 13 for holding the band tautly in position.

50 This means includes a slot 14 formed in the end portion of one of the ends of the band and receiving a portion 13a from the other end of the band. The arrangement is such that because of this interlocking of the end portions of the band it is possible to pull the ends of the

band in opposite directions and so tightly engage the band in position. After the band is tightly engaged it is proposed that the end portion 13a be bent outwards, as illustrated in Fig. 2, for permanently holding the band in the taut condition.

The inner cap 12 has an end wall 12a engaging over the end of the container neck 11, and a side wall 12b extending around the sides of the neck 11. The flexible band 13 is engaged 10 around the side wall 12b. The outer cap 10 has an end wall 10a engaged across the end wall 12a of the inner cap, and a side wall 10b which is superimposed over the side wall 12b of the inner cap.

15 The inner cap 12 may be of relatively soft material, such as paper, metal or other suitable material to act as a seal. The outer cap 10 may be of stiff metal or other strong material.

20 Cooperative means are provided between the band 13 and the outer cap 10 for holding same fixed in relatively adjusted positions. These means include a hook portion 13b formed on one end of the band 13 and engaged through an opening 15 formed in the side wall 10b of 25 the outer cap. The band 13 is also formed with a tongue 16 stamped out from the material thereof and engaged through an opening 17 in the side wall 10b of the outer cap for assisting in holding these parts in relatively fixed positions. 30

25 The air tight cap, according to this invention, is engaged upon a container in the following manner. The tongue 16 of the band 13 is normally in a radially extended position as indicated by the dot and dash lines 16'. In this condition the tongue projects through the opening 17. The hook 13b is tightly engaged upon the material of one side of the opening 15. The band 13 is expanded and loose. The cover in this condition is engaged over the neck 11. The outer cap 10 is formed with a large opening 18 in the side wall 10b thereof. Through this opening it is possible to grip the end 13a of the band 13. This end 13a is normally loosely extended through the slot 14.

40 The end 13a is tightly pulled in a clockwise direction, as viewed in Fig. 2. This causes contraction of the band and causes it to tightly press the side wall 12b of the inner cap against the outer face of the neck 11. The end portion 13a is then bent counter-clockwise, as viewed in 45 Fig. 2, so that it engages the material at the end of the opening 14. This serves to hold the band 13 permanently in position. The extended end of the tongue 16 is then bent laterally to the 50

55

position as shown by the full lines in Fig. 2. The cover is now securely on the container.

It is advisable that the outer end of the neck 11 be formed with a bead 11^a which will assist in preventing the cover from slipping off the neck.

While I have illustrated and described the preferred embodiments of my invention, it is to be understood that I do not limit myself to the precise constructions herein disclosed and the right 10 is reserved to all changes and modifications coming within the scope of the invention as defined in the appended claims.

Having thus described my invention, what I claim as new, and desire to secure by United 15 States Letters Patent is:—

1. An air tight cover for a container, comprising an outer cap for engaging over the neck of a container, an inner cap of relatively flexible material within said outer cap and adapted to engage 20 over the neck of said container, a band of flexible metal between said caps and encircling said inner cap and adapted to clamp the inner cap tightly against said neck, cooperative means between the ends of said band for holding the band in a very 25 taut condition, and cooperative means between said band and outer cap for holding same fixed in relatively adjusted positions.

2. An air tight cover for a container, comprising an outer cap for engaging over the neck of a 30 container, an inner cap of relatively flexible material within said outer cap and adapted to engage over the neck of said container, a band of flexible metal between said caps and encircling said inner cap and adapted to clamp the inner 35 cap tightly against said neck, cooperative means between the ends of said band for holding the band in a very taut condition, and cooperative means between said band and outer cap for holding same fixed in relatively adjusted positions, 40 said band being formed with a slot near one end portion thereof, and the other end portion of the band being reduced and engaged through this slot whereby the ends of the band may be relatively pulled in opposite directions to clamp the band in position.

3. An air tight cover for a container, comprising an outer cap for engaging over the neck of a container, an inner cap of relatively flexible material within said outer cap and adapted to engage 45 over the neck of said container, a band of flexible metal between said caps and encircling said inner cap and adapted to clamp the inner cap tightly against said neck, cooperative means between the ends of said band for holding the

band in a very taut condition, and cooperative means between said band and outer cap for holding same fixed in relatively adjusted positions, 5 said band being formed with a slot near one end portion thereof, and the other end portion of the band being reduced and engaged through this slot whereby the ends of the band may be relatively pulled in opposite directions to clamp the band in position, the wide end of said band being formed with a hook portion engaged through an opening in the side wall of the outer cap for anchoring this end of the band.

4. An air tight cover for a container, comprising an outer cap for engaging over the neck of a container, an inner cap of relatively flexible material within said outer cap and adapted to engage over the neck of said container, a band of flexible metal between said caps and encircling said inner cap and adapted to clamp the inner cap tightly against said neck, cooperative means between the ends of said band for holding the band in a very taut condition, and cooperative means between said band and outer cap for holding same fixed in relatively adjusted positions, 10 said band being formed with a slot near one end portion thereof, and the other end portion of the band being reduced and engaged through this slot whereby the ends of the band may be relatively pulled in opposite directions to clamp the band in position, the wide end of said band being formed with a hook portion engaged through an opening in the side wall of the outer cap for anchoring this end of the band.

5. An air tight cover for a container, comprising an outer cap for engaging over the neck of a container, an inner cap of relatively flexible material within said outer cap and adapted to engage over the neck of said container, a band of flexible metal between said caps and encircling said inner cap and adapted to clamp the inner cap tightly against said neck, cooperative means between the ends of said band for holding the band in a very taut condition, and cooperative means between said band and outer cap for holding same fixed in relatively adjusted positions, comprising a tongue stamped from the material of the band and engaged through a slot in the outer cap and having its outer end portion bent against the face of the cap.

SOUREN KAZANJIAN.
